(57) **CLAIM**

The ornamental design for a shoe, as shown and described.

DESCRIPTION

FIG. 1 is a perspective view of a shoe showing my new design;

FIG. 2 is a top plan view of my new design;

FIG. 3 is a bottom plan view of my new design.

FIG. 4 is a left-hand side elevational view of my new design;

FIG. 5 is a right-hand side elevational view of my new design;

FIG. 6 is a front elevational view of my new design; and,

FIG. 7 is a back side elevational view of my new design. The sole for the shoe shown in the figures is made of a plastic material molded as a one-piece unitary structure. The strap is also made of a plastic material molded as a one-piece unitary structure.
